MOLDING DEVICE

Mario T. David, Los Angeles, Calif.

Application May 3, 1948, Serial No. 24,755

5 Claims. (Cl. 22—69.1)

1

The present invention relates to an improved molding device useful, for example, and not as a limitation, by dentists and laboratory technicians in molding or casting operations.

An object of the present invention is to provide an improved device useful in molding operations characterized by the ease in which it may be operated to produce relatively large necessary pressures.

Another object of the present invention is to provide an improved molding device having a trigger element which may be easily moved by the use of a person's finger against the action of spring means which is subsequently effective to move an element at a relatively large speed in the development of instantaneous high pressures.

Still another object of the present invention is to provide an improved molding device characterized by the incorporation therein of a novel tripping mechanism actuatable by a person's finger.

Yet a further object of the present invention is to provide an improved molding device having a plurality of tension springs, each being fully effective in moving an element to produce relatively large pressures from a cocked position but incorporating a novel finger-operated tripping mechanism which includes a tripping or sear element normally held in locked position by only one of such plurality of springs, so that a minimum amount of finger pressure is required to release the energy stored in the plurality of springs to allow such member to move under the influence of such plurality of springs.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a view in side elevation of the novel molding device embodying the present invention.

Figure 2 is a view of the molding device shown in Figure 1 but with the cap member in its lowermost position.

Figure 3 is a top plan view of the apparatus shown in Figure 2.

Figure 4 is a sectional view taken substantially on the line 4—4 of Figure 2.

Figure 5 is a perspective view of one of the plaster cup holding elements shown in Figure 6.

2

Figure 6 is a sectional view taken substantially on the line 6—6 of Figure 2.

Figure 7 is a sectional view similar to the sectional view shown in Figure 1 but with the parts in a different operating condition.

The device includes a stationary base member 10 arranged to hold a mold 11, a spring-biased cap member 12 pivotally mounted with respect to said base member and movable from its cocked position shown in Figure 1 to its other extreme position shown in Figure 2 upon operation of the pivotally mounted finger-operated trigger member 13, the member 13 being effective, as described in greater details below, to release the cocking mechanism whereby the tension springs 14, 15 are fully effective to move the cap member 12 containing the wet asbestos or "Moldene" material 16 into engagement with the upper rim 18 of the mold 11 to thereby forceably eject preheated molding materials, such as gold 20, through the channel 21 into the preformed cavity 22 of predetermined configuration. The mold 11 per se is of conventional structure and made in accordance with conventional means and comprises a cylindrical plaster body encased within the sheet metal retaining member 23, which, in turn, is resiliently mounted with respect to the base member 10 by a pair of diametrically and oppositely disposed spring-urged contacting members 24, 25, each one of these contact members 24, 25 being of identical arcuate shape and having affixed thereto a guide rod 26, 27, respectively, passing through corresponding cylindrical guide bearings 28, 29 in the cylindrical frame member 30 attached to the base member 10 with corresponding coil compression springs 26A, 27A disposed between the housing 30 and the respective contact members 24, 25 to press these members inwardly against cylindrical mold 11.

40 This mold member 11 is dished at its upper end as shown in Figure 6 to form a suitable retaining member for the molding material 20 either while in the solid form or while being heated by a gas or acetylene flame. The channel 21 and preformed cavity 22 in the mold 11 is preformed in conventional manner well known to those skilled in the art. Of importance, and the basis for the present application, is the mechanism whereby the molding material 20 is forced quickly and under great pressure through the channel 21 into the preformed cavity 22 of predetermined shape.

45 The mechanism for accomplishing this purpose includes the cap member 12 which is moved with great force and with a bang in the direc-

tion of mold 11. The resulting shock forces developed upon contact of the wet asbestos or "Moldene" material 16 within the cap member 12 with the mold 11 are absorbed or transmitted to the base member 10 through the outer cylindrical metal sheath 23. The other dynamic forces in the moving cap member 12 are transmitted to the base 10 through the frame 30.

The cap member or percussion produced in member 12 is in the form of a cylindrical inverted dish with an inwardly turned annular flange 10A adapted to retain therein the "Moldene" or asbestos material 16 and carries a hook 10B to facilitate upward manual movement to its cocked position shown in Figure 1 against the action of the tension springs 14, 15. The cap member 12 has extending therefrom the arm 32 with the bearing sleeve 34 formed therein through which the pivot pin 35 passes, the pivot pin 35 having its ends clamped by bolts 37, 38 in the bifurcated extensions 39, 40, respectively, of the base member 30. These bifurcated extensions 39, 40 extend further outwardly and form into a centrally disposed extension 41.

The coil tension spring 14 has one of its ends attached to the base member extension 41 and the other one of its ends attached to the extension 32 of the pivotally mounted cap member 12. Also mounted on the extension 32 is a pivotally mounted catch member 32A forming a portion of the cocking mechanism.

The spring 15 has one of its ends mounted on a threaded rod passing through and held in place on the cap member 12 by the knurled adjusting screw 42 which is adjustable to preset the tension in spring 15 to a predetermined magnitude. The lower end of the spring is attached to the lever member 44 which is pivotally mounted on the pivot pin 45 held in the spaced bracket members 46 on the base member 10. This spring member 15 is attached to the lever member 44 at a point intermediate the pivot pin 45 and the most inward end of the lever member 44 upon which a hook member 49 is fastened to co-operate with the catch member 32A, the other end of the lever member 44 being engageable with the inwardly extending end of the pivotally mounted finger-operated lever member 13. Lever member 13 is pivotally mounted on pivot pin 50 which is held in bracket member 52 mounted on the base 10.

Thus, the springs 14, 15 tend to rotate the cap member 12 in the clockwise direction in Figure 1 and simultaneously the spring 15 tends to rotate the lever member 44 also in the counter-clockwise direction in Figure 1 to press the hook member 49 carried thereon into engagement with the cap member 32A mounted on the extension 32 of the cap member 12. This lever member 44 may be rotated counterclockwise against the action of spring 15 to break the connection between the hook member 49 and the catch member 32A by manual operation of the finger-operated lever member 13. In such case it is noted that movement of the finger-operated member 13 is recessed only by the tension in spring 15, while both springs 14, 15 are effective, once the connection between elements 32A and 49 is broken to move the cap member 12 downwardly with tremendous force to allow the cap member to assume the position shown in Figure 12.

When the cap member is in closed position, as shown in Figure 12, an auxiliary spring member 60 aids in holding the cap 12 in its closed position, the spring member 60 being deflected

laterally when and as the cap member 12 moves from the position shown in Figure 1 to the position shown in Figure 2 and when the cap is in the latter position returns to engage the top of the cap 12 to firmly press it downwardly.

In order to cock the cap member 12 in its position shown in Figure 1 the spring holding member 60 is first moved outwardly and then the cap member 12 is raised by applying a force to the handle 10B to rotate such cap member about the pin 35. In such upward movement of cap member 12 the springs 14, 15 are tensioned, the catch member 32A slides over the hook 49 and, subsequently, after the manual forces are released the cap member 12 tends to return to its initial position shown in Figure 2 but is prevented from doing so upon engagement with the hook member 49 with the catch member 32A as shown in Figure 1. Thereafter, to release the connection between the hook member 49 and the catch member 32A it is necessary to operate the finger-operated lever 13.

This finger-operated lever 13 is operated immediately after the molding material 20 is being heated by a gas flame, so that there is substantially no appreciable time interval between the cessation of heating of the molding material 20 and the application of percussion or compression forces to the upper surface thereof, which percussion forces cause the molding material 20 to flow through the channel 21 into the preformed hollow portion 22 of the predetermined shape.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A molding device of the character described comprising a base member arranged to releasably hold a mold; a cap member pivotally mounted on said base member and movable in a path to enclose the interior of said mold held in said base and to force molding material in said mold; a first tension spring having one of its ends connected to said cap member and the other end to said base tending to move said cap member into contact with said mold; a pivoted catch member mounted on said cap member; a first lever member pivoted on said base member having one of its ends engageable with said catch member to maintain said cap member in cocked position; a second tension spring having one of its ends connected to said cap member and the other of its ends connected to said lever member tending to move said cap member into proximity with said mold and pressing said lever member into engagement with said catch member; and a finger-operated lever member on said base member movable to contact and to move said first lever member against the action of said second spring to release the connection between said first lever and said catch.

2. A molding device of the character described in which a cap member is moved under the action of two separate tension springs to enclose the interior of a mold held in a base member, the subcombination comprising, a base member; a cocking mechanism comprising a pivoted catch member on said cap member; a first lever member pivotally mounted on said base member and

adapted to engage said catch member, one of said two springs having one of its ends attached to said cap member and the other one of its ends attached to said lever member; and a finger-operated lever pivoted on said base member and movable to contact and to move the first lever against the action of only said one spring to release the connection between said pivoted catch and said first lever member.

3. A molding device of the character described, comprising a base member; a spring-biased contact member arranged to hold a mold firmly with respect to said base; a pivoted cap member mounted on said base; a first tension spring having one of its ends connected to said cap and the other of its ends connected to said base tending to rotate said cap in the direction of the mold, said cap member having mounted thereon a pivoted catch member; a first lever member pivoted on said base member adapted to engage said catch member to maintain said cap member in cocked position; a second tension spring having one of its ends attached to said cap member and the other one of its ends attached to said lever member; and a finger-operated lever pivoted on said base member and movable to contact and to move said first lever against the action of said second spring to break the connection between said first lever and said catch to thereby trip the cap whereby it may move under the influence of both said first and said second springs.

4. In a molding device of the character described, a base member adapted to hold a mold; a cap member pivotally mounted on said base 35 and movable in the direction of said mold; a

pivoted catch member mounted on said cap member; a first lever member pivoted on said base member having one of its ends adapted to releasably engage said catch member to latch said cap in position; a spring having one of its ends attached to said cap member and the other one of its ends attached to said lever member adapted to move said cap member in the direction of said mold and to press said lever into latching engagement with said catch; and finger-operated means on said base member movable to contact and to move said lever out of engagement with said catch to thereby allow said cap member to move in the direction of said mold under the influence of said spring.

5. The invention defined in the next preceding claim characterized by the fact that there is an adjustable screw threaded extensible connection between said spring and said cap to provide for 20 adjustment of said spring.
